UNITED STATES PATENT OFFICE.

JOHN J. RECTENWALD, OF MOUNT OLIVER BOROUGH, PENNSYLVANIA.

LIFE-SAVING DEVICE.

996,362.

Specification of Letters Patent. Patented June 27, 1911.

Application filed August 13, 1910. Serial No. 577,050.

To all whom it may concern:

Be it known that I, JOHN J. RECTENWALD, a citizen of the United States of America, residing at Mount Oliver borough, in the 5 county of Allegheny and State of Pennsylvania, have invented certain new and useful Improvements in Life-Saving Devices, of which the following is a specification, reference being had therein to the accompanying 10 drawing.

This invention relates to life saving devices especially designed for bi-planes, mono-planes, gliders and other types of air craft, and the invention has for its primary 15 object to provide a machine of the above type with positive and reliable means for maintaining the same afloat should it alight in a river, lake or other body of water.

A further object of the invention is to 20 furnish an air craft with a fire extinguisher that will permit the operator of the machine extinguishing a fire that might occur upon the air craft or in the vicinity of the same.

25 A still further object of the invention is to provide an air craft with floats for maintaining the same upon a body of water and with a propeller for moving the air craft to shore after having landed in a body of 30 water.

These and such other objects as may hereinafter appear are attained by the novel construction, combination and arrangement 35 of parts to be hereinafter specifically described and then claimed.

Reference will now be had to the drawing, wherein:—

Figure 1 is a perspective view of a bi-plane constructed in accordance with this 40 invention, Fig. 2 is a front elevation of a portion of the same, partly broken away and partly in section, Fig. 3 is a bottom plan of a portion of the bi-plane, Fig. 4 is a side elevation of a portion of the air craft, showing a water propeller, and Fig. 5 is a bottom plan of the same.

In the accompanying drawings there is 45 illustrated a bi-plane of the ordinary type, the bi-plane having the longitudinal rudder frames 1 thereof connected by straps 2 beneath the lower plane of the machine, and suitably connected to said straps, as at 4 are collapsed flexible bags or receptacles 6, which abut against each other and which 50 when inflated constitute floats capable of sustaining the machine upon the surface of

a body of water. Said bags or receptacles 6 constitute floats and of a combined width substantially equal to the distance between the longitudinal rudder frames 1.

The frames 1 support the usual foot-rest 7 and this rest is provided with straps 8 similar to the straps 2, to which is connected a large bag or receptacle 9 adapted to be inflated to constitute a float co-operating 65 with the floats beneath the bottom plane 3 of the machine.

The bags or receptacles 6 and 9 are connected by branch tubes or hose 10 to a pipe 11 in communication with a tank or reservoir 12, said tank being located in the rear of the driver's seat 13 of the machine. The tank 12 is adapted to contain carbon-dioxide or any suitable gas or gas producing substances or chemicals, the air or gas being 70 retained under pressure, and the pipe 11 is provided with a valve 14 convenient to the operator's seat 13, whereby the valve 14 can be opened and the contents of the tank or reservoir 12 admitted to the bags or receptacles 6 and 9.

It is preferable to store carbon-dioxide (CO₂) or other fire extinguishing gases in the tank or reservoir 12, whereby the tubes 10 can be detached from the floats and the 85 carbon-dioxide or other gas used for extinguishing fire as might occur by a leakage in the gasoline tank, pipes or other parts of the operating mechanism of the air craft.

It is a well known fact that it is the practice of aviators to follow wherever possible 90 rivers and bodies of water and thereby lessen the danger of their lives being lost should an accident occur. As an additional safety factor, I provide the floats in connection with the air craft, not only to save the life of the operator of the craft, but to prevent the craft from sinking in the body of water and becoming a total loss. When an aviator discovers that he must alight upon 95 a body of water, it is only necessary for him to open the valve 14 to inflate the floats 6 and 9, and these floats are of a sufficient size to support the machine upon the surface of 100 the body of water.

In Figs. 4 and 5 of the drawings I have 105 illustrated the air craft as provided with a water propeller, the propeller being designated 20 and mounted upon the end of a shaft 21, journaled in bearings 22 carried by frames 23 located at the base of the air craft. The shaft 21 is provided with a sprocket

wheel 24 and this wheel is driven by a chain 25 passing over a sprocket wheel 26 mounted upon the main driven shaft 27 of the air craft. The rear rudder 28 of the air craft 5 can be used for steering the machine either in the air or in water.

It is in connection with the additional water propeller that I reserve the right to equip the supporting wheels of the air craft 10 with paddles or blades that will serve functionally for propelling the craft when upon a body of water, or assist the ordinary air propeller when the craft is in flight. The paddles or blades can be permanently or de- 15 tachably connected to the wheels and so arranged as to materially assist the water and air propellers. Furthermore, in lieu of the tank or reservoir, I reserve the right to utilize at any desired time the exhaust from the 20 gasoline engine for inflating the floats.

Many variations may be made in the details of construction without departing from the spirit of my invention, the first or genus of which consists in the broad idea of providing an aeroplane with floats so arranged as to be inflated in case of accident, and with a water propeller for moving the air craft upon a body of water.

While I have herein illustrated and de- 30 scribed the means which I prefer for carrying out my invention, it is obvious that other and equivalent means can be employed for that purpose, and I therefore do not limit the scope of my invention further than as 35 defined in the claims hereto appended.

What I claim is:—

1. In an air craft, a body-portion, a pair of inflatable bags arranged at the bottom of 40 said body and constituting when inflated a pair of floats in abutting engagement, a res-

ervoir carried by the body and in communication with said floats, adapted to supply a fluid thereto thereby inflating the floats, means for controlling the inflation of said floats, straps for securing the floats to said 45 body, a foot rest supported by the body and disposed at an inclination, an inflatable bag secured to the bottom of the foot rest and adapted when inflated to constitute a float, 50 said float of the same width as said body, and means for establishing communication between the float attached to the foot rest and said reservoir whereby a fluid for inflating the float can be supplied thereto.

2. In an air craft, a body portion, a pair of inflatable bags arranged at the bottom of 55 said body and constituting when inflated a pair of floats in abutting engagement, a reservoir carried by the body and in communication with said floats adapted to supply a fluid thereto thereby inflating the floats, means for controlling the inflation of said floats, straps for securing the floats to said 60 body, the combined width of said floats being substantially equal to that of the width of said body, a foot rest supported by the body and disposed at an inclination, an inflatable bag secured to the bottom of the foot rest and adapted when inflated to constitute 65 a float, said float of the same width as said body, and means for establishing communication between the float attached to the foot rest and said reservoir whereby a fluid for inflating the float can be supplied thereto. 70

In testimony whereof I affix my signature in the presence of two witnesses.

JOHN J. RECTENWALD.
